FOREIGN PATENT DOCUMENTS

WO WO 2018/053584 A1 3/2018

Primary Examiner — Holly E Thurman*Assistant Examiner* — Leisha N Price(74) *Attorney, Agent, or Firm* — Finnegan, Henderson, Farabow, Garrett & Dunner, LLP(57) **CLAIM**

The ornamental design for a radiator clip, as shown and described.

DESCRIPTION

FIG. 1 is a front, top, left perspective view of a radiator clip showing the new design;

FIG. 2 is a rear, bottom, right perspective view thereof;

FIG. 3 is a bottom plan view thereof;

FIG. 4 is a top plan view thereof;

FIG. 5 is a left-side elevation view thereof;

FIG. 6 is a right-side elevation view thereof;

FIG. 7 is a front elevation view thereof;

FIG. 8 is a rear elevation view thereof; and,

FIG. 9 is a cross-sectional view thereof as indicated in FIG. 8.

The broken lines of even length shown in the drawings illustrate portions of the radiator clip that form no part of the claimed design.

1 Claim, 9 Drawing Sheets(56)
